UNITED STATES PATENT OFFICE.

ARTHUR ATWATER KENT, OF ARDMORE, PENNSYLVANIA.

VARIABLE-COIL STRUCTURE.

Application filed October 16, 1923. Serial No. 668,905.

To all whom it may concern:

Be it known that I, ARTHUR ATWATER KENT, a citizen of the United States, residing at Ardmore, in the county of Montgomery and State of Pennsylvania, have invented certain new and useful Improvements in Variable-Coil Structures, of which the following is a specification.

My invention relates to apparatus comprising relatively rotatable coils utilizable for any suitable purpose or in any desired way, but particularly as a variometer or a vario-coupler, or the like, in systems or circuits employing or traversed by fluctuating or alternating current, and particularly high frequency current such as used in systems of radio telephony, telegraphy and the like.

My invention resides in apparatus of the character referred to comprising a shaft, preferably divided into sections insulated from each other, supporting the rotatable coil structure, and co-acting with suitable bearing or journal supports, the shaft and supports being provided with means of the character hereinafter described for effecting and maintaining good electrical contact and co-action between shaft and supports and for effecting friction sufficient to retain the rotatable coil structure in any position to which adjusted.

Further in accordance with my invention, the stationary coil structure comprises coil supports of molded insulating material having integral therewith extensions or lugs for securing them to supports and for accommodating binding posts or other connecting means.

Further in accordance with my invention, the rotatable coil structure comprises coil supports molded of insulating material secured to each other and to the shaft, and preferably having integral closed ends.

Further in accordance with my invention, to one of the posts or supports, to which the stator members are secured, is secured a panel, from the front of which the rotor shaft is operable and upon which is a scale; and in the case of the vario-coupler, the panel carries switches for varying the inductance of the stator winding by large and small steps.

My invention resides in the features of construction and arrangement hereinafter described.

This application is in part a continuation 55 of my application Serial Number 564,996, filed May 31, 1922.

For an illustration of some of the various forms my invention may take, reference is to be had to the accompanying drawings, in 60 which:

Fig. 1 is a side elevational view of apparatus embodying my invention.

Figs. 2 and 3 are elevational views at opposite ends of the structure of Fig. 1. 65

Fig. 4 is a longitudinal sectional view, some parts in elevation, of the apparatus shown in Fig. 1.

Fig. 5 is a front elevational view of the structure shown in Fig. 1. 70

Fig. 6 is a fragmentary sectional view showing a modification of means for securing said coil supports to each other and to the shaft.

Fig. 7 is a fragmentary plan view of the 75 structure shown in Fig. 6.

Fig. 8 is a vertical sectional view, parts in elevation, of a vario-coupler embodying my invention.

Fig. 9 is a front elevational view of the 80 structure shown in Fig. 8.

Fig. 10 is a vertical sectional view taken on the line 10—10 of Fig. 8.

Fig. 11 is a fragmentary side elevation of 85 the structure shown in Fig. 8.

Fig. 12 is a vertical sectional view on the line 12—12 of Fig. 10.

Fig. 13 is a fragmentary sectional view indicating a modified mode of taking out the 90 taps from the stator winding.

Fig. 14 is a diagrammatic view of one mode of utilizing the vario-coupler.

Referring to Figs. 1 to 5 inclusive, 1 and 2 are substantially similar coil supports of molded insulating material, such as bakelite, condensite or the like. Each is provided with a preferably spherical outer surface 3 lying between the raised edges 4 for receiving and accommodating the coils A and B, of copper or other suitable wire, 100 solid or stranded, the neighboring convolutions or turns being insulated from each other, as by the insulating covering of the wire itself, such insulation being either fabric, as silk or cotton, or enamel, or any other 105 suitable material.

The members 1 and 2 are cup-shaped, their edges being positioned adjacent or in

contact with each other in the plane of the axis of rotation of the metal shaft comprising the sections C and D, in axial alignment and secured to each other by the block 5 or sleeve of insulating material 5, a washer or member 6 of insulating material separating the adjacent ends of the shaft sections to insulate them from each other.

The aforesaid coil supports 1 and 2 are 10 cup-shaped in virtue of the fact that at their outer ends they are closed by the integral closure walls 7, preferably thinner than and offset from the outer face of the flanges 8 of the members 1 and 2.

15 The employment of the closure members 7 cheapens the molding operation in that it is simpler and cheaper to mold the members 1 and 2 with such walls or diaphragms 7, as distinguished from the case where the members 7 are absent, in which case the members 1 and 2 would have at 9, 9 circular apertures communicating with the interior of the assembly structure 1, 2.

20 The walls 7 have a further advantage in 25 that they form with the members 1 and 2 when assembled a substantially completely closed hollow structure, preventing access of moisture, dust, etc., to the interior of the members 1 and 2.

25 The members 1 and 2 are secured to each 30 other by any suitable means, such, for example, as the bolts 10 having screw heads 11 received in depressions or countersinks in the flanges 8 and having threaded thereon 35 at their opposite ends in similar depressions or countersinks in the flanges 8 the nuts 12. The bolts 10 are disposed adjacent, but on opposite sides of the shaft structure, tension upon the bolts as applied

40 by the nuts 12 serving to clamp the coil supports 1 and 2 securely to the shaft and to hold the members 1 and 2 in fixed position with respect to each other as a unit rotatable with the shaft. The outer ends 45 of the coils A and B are connected by the conductors 13 and 14, respectively, with the shaft sections D and C, respectively, while the inner ends of the coils A and B are connected to each other by the conductors 15 and 16 connected to each other at 17. Accordingly, the coils A and B are in series with each other and the rotary coil unit or rotor has terminals in the shaft sections C and D. The direction of winding of the

50 coils A and B or their mode of connection is preferably such that they operate cumulatively, as required in ordinary practice. It will, of course, be understood, however, that while the coils A and B are shown as connected in series with each other, they may be connected in parallel with each other, it being understood, however, that the series connection is preferred.

55 Each of the members 1 and 2 is provided with a hole α and a projecting pin or lug b ,

disposed, for example, as indicated in Figs. 1 and 4. When the edges of the members 1 and 2 are brought together, the pins or lugs b on the members engage and register in the holes α in the opposite members, whereby the members 1 and 2 are properly positioned and held accurately in position with respect to each other.

At 18 and 19 are shown metallic posts or supports forming bearings for the shaft structure and supporting a stationary coil or stator structure. The support 18 has the bore or hole 20 through which the shaft section C extends, preferably loosely. At 21 the member 18 has a conical, spherical or other similar counterbore in which engages the conical, spherical or similar end of the collar 22 secured upon the shaft section C adjacent or abutting against the adjoining edges of the coil supports 1 and 2.

25 In the support 19 the shaft section D has a relatively short bearing in the hole 23 in which the shaft section fits relatively snugly, the member 18 having the relatively larger bore 24 through which the shaft D loosely extends. Secured by the screws 25 to the member 19 is the leaf spring 26 having an aperture 27 in which is received the conical end 28 of the shaft section D, the aperture 27 being relatively larger than the conical end 28, and the upper edge only of the aperture 27 engaging upon the conical surface 28. The spring 26 is so biased that its upper end tends to move from left toward the right, Fig. 4, toward the post 19, thereby thrusting the shaft structure toward the right, causing the conical collar 22 firmly and snugly to engage in the conical seat 21 in the member 18 to effect and maintain a good low resistance connection between the shaft section C and the post 18, and at the same time to effect a substantial and accurate bearing for the shaft. The thrust of the spring 26 upon the conical end 28 of shaft section D also presses the left end of the section D downwardly into good bearing relation with the post 19 at 23, simultaneously effecting a good electrical connection between the shaft section D and the post 19.

30 By the structure described, an accurate and substantial shaft mounting and structure are provided, and at the same time low resistance electrical connections are made in effect between the terminals of the coils A and B and the posts 18 and 19; and the action of the spring 26 serves also to effect sufficient friction at the shaft bearings for ensuring that the rotatable coil structure will remain in, and not be easily displaced from, any position to which it may be rotated upon rotation of the shaft section C by the operator.

35 The movable coil structure comprising the aforesaid members 1 and 2 and the coils A and B

and B carried thereby is rotatable within the stationary coil structure comprising the stator members 29 and 30, of molded insulating material, as bakelite, condensite, etc., and each having the integral lugs or projections 31 and 32 on opposite ends. The extensions 31 and 32 have faces preferably in substantially the same planes with the faces of the members 29 and 30 at their sides of larger diameter. As indicated in Fig. 2, the extensions or lugs 32, 33 on the members 29 and 30 lie on opposite sides of the post 19 and are secured thereto by the bolts or screws 33. Similarly, at the opposite ends the lugs or extensions 31, 31 upon the members 29 and 30 are disposed on opposite sides of the post 18 and are secured thereto by the bolts or screws 34. The inner surfaces of the coil supports 29 and 30 are of any suitable form, preferably spherical, as indicated, and concentric with the rotatable coil structure. Disposed upon the inner surfaces of the supports 29 and 30 are the coils E and F, which may be of material and structure similar to the coils A and B. One terminal of the coil E, as that nearest the post 19, is connected thereto by the conductor 35 passing through a hole in the member 29 or its extension or lug 32 and held in electrical contact with the post 19 by the screw 36. The other terminal of the coil E is connected to the binding post 37 comprising a threaded rod or stud 38 molded in or threaded into the boss 39 integral with the member 29, the binding nut 37 being threaded upon the post 38, and a conductor 40 forming a part of the coil E or connected to a terminal thereof being clamped by the nut 37. Similarly, one terminal of the coil F is connected by conductor 41 with the post 18; the screw 42 holding the conductor 41 in engagement with post 18; and the outer end of the coil F connects by conductor 43 with the binding post structure comprising the threaded rod 44, molded in or threaded into the boss 45 integral with the member 30, and the nut 46 threaded upon the rod 44.

Accordingly, the binding posts 37 and 46 constitute the two terminals of the apparatus. From the binding post 37 the circuit or path extends through the winding E to the post 19, thence through the shaft section D, thence through the inner or rotor coils A and B in series with each other, to the post 18, and thence through the coil F to the binding post 46.

There is accordingly provided a combination of stationary and movable coils in series with each other, constituting an inductance, which is variable upon rotation of the inner coil structure, for any suitable purpose, particularly for changing the inductance of a high frequency circuit such as used in radio telephone, telegraph or other systems.

The apparatus as described may be mounted in any suitable or desirable way. As indicated, the posts 18 and 19 are provided with feet or pedestals 47 by which the structure may be secured to a horizontal, vertical or other surface or member. Or when the apparatus is to be supported upon a vertical board or panel, as for example, a vertical panel or switchboard of a radio receiving or transmitting apparatus, the post 18 may be provided with the threaded holes 48 adapted to receive screws for holding the member 18 to the vertical board or panel, generally upon the rear thereof, the shaft section C being of sufficient length to extend to the front of the panel or board, and there provided with a handle or dial for turning the rotatable coil structure to predetermined or any desired position.

There may be provided, particularly when the apparatus is to be mounted or supported by the feet 47, a panel or face plate P, preferably of molded insulating material, such as condensite, bakelite, etc., having molded integral therewith the bosses 49 which abut against the post or support 18 to which the panel is secured by the screws 50 extending through it and the bosses 49 and threaded into the post 18. The shaft section C extends through an aperture in the panel P and has secured thereto the hub or sleeve 51 to which is attached the knob or handle 52 for rotating the rotor with respect to the stator, the extent of movement of the rotor or the relative positions of the rotor and stator being indicated by the pointer 53 secured to the hub 51 and coacting with the scale or dial 54 which may be mounted upon or directly engraved upon the raised dial or scale element 55 molded integral with the panel P.

Referring to Figs. 6 and 7, there is illustrated a modified structure for holding the inner coil supports 1 and 2 to each other. Each of the members 1 and 2 adjacent its periphery at opposite ends is provided with a channel or depression 56, a bolt or screw 57 extending through the adjacent flanges of the members 1 and 2 and clamping them to each other. The wires of the coils A and B extend across or bridge the relatively narrow channels or grooves 56. The bolts or screws 57 clamp the members 1 and 2 to each other and to the shaft sections.

Referring to Figs. 8 to 12 inclusive, a structure in principle similar to that above described is disclosed. In this case, however, the rotatable coil structure is not connected to the stationary coil structure, but is in inductive relation therewith, the stationary and movable coil structures comprising in effect the coils or windings of a high frequency or oscillation transformer or variocoupler of which the outer coil structure or stator may be the primary, as when connected in the antenna path or circuit, while the rotatable

coil structure or rotor may be the secondary which may be in a circuit attuned to the received oscillations and associated with suitable detector or wave responsive means.

8 In this case again the coils A and B are connected in series with each other, and the terminals of the combination are connected by conductors 13 and 14 to the shaft sections D and C, which in turn are in electrical communication with the posts 18 and 19, which may therefore be considered terminals of the secondary of the coupler or transformer, connections to the secondary circuit being made by conductors which may be held by the binding posts 18^a and 19^a to the posts 18 and 19, respectively.

9 The primary or stationary coil structure again comprises stator members 29 and 30. In this case, however, the coils E and F are 20 disposed upon the outside of the members 29 and 30 upon conical surfaces, though it is understood that spherical or any other shaped surfaces may be employed.

10 As indicated in Fig. 14, the coils E and F 25 may be connected in series with each other between the antenna or receiving conductor R, or equivalent means, and the earth or counter-capacity G, and the rotor or secondary A, B, may have its terminals 18^a and 19^a connected to any suitable receiving circuit, as for example to the grid circuit of an amplifying or detector tube of the audion type. Different amounts of the primary or 30 stator winding E, F are brought into circuit 35 for tuning purposes by the switches 58 and 59, the former having a plurality of switch contacts 60 connected by a group of taps or lead conductors 61 with suitable points upon the stator coils E and F, and the latter having 40 a plurality of switch contacts 62 connected by a group of taps or conductor leads 63 with a plurality of points upon a portion of the stator coil F. The switch 58 effects coarse 45 adjustment and the switch 59 fine adjustment of the number of turns brought into circuit, there being preferably a single turn or convolution of the winding F between contacts 62 and a plurality of turns of stator coils E and F between the contacts 60.

50 As indicated in Fig. 9 the fine and coarse switches are disposed upon the panel P on opposite sides of the vertical axis of symmetry and preferably below the pointer 53 and scale 54.

55 The two switches are similar, and the description of one will suffice for both. Referring more particularly to Fig. 12, the switch arm 58 is secured to and electrically connected with the metallic shaft 64 extending 60 through and having a bearing in the panel P and carrying at its one end the operator's handle or knob 65 for rotating the switch blade 58 over the contacts 60, the lugs or bosses 66, preferably molded integral with the panel P, serving as stops to

limit the movements of the switch in opposite directions. Binding post screw 67, having a roughened head 68 is preferably molded in the panel P and projects to the rear thereof where there is threaded thereon 70 the binding screw or nut 69 for switch 58 and 70 for the switch 59. Surrounding the screw 67 and electrically connected therewith is the connector spring 71 having a perforation through which the shaft 64 extends and 75 disposed between the panel P and the collar 72 secured by screw 73 to the shaft 64, the spring 71 pressing toward the left on the collar 72, as viewed in Fig. 12, thereby holding the switch 58 firmly in engagement with 80 the switch contacts 60. The switch contacts have shanks 74, preferably roughened and molded in the panel P, terminating on the rear of the panel in the studs 75 to which the taps or connector leads are soldered or otherwise electrically connected. 85

90 While in the example above described the taps or connector leads 61 and 63 extend for the most part directly from the exterior of the coils E and F to the studs 75, these taps may be otherwise disposed as indicated in Fig. 13 which shows the taps or lead conductors 61 extending through holes 76 in the end flange 29^a of stator member 29 to the interior of the stator member 29 and thence through holes 77 to the appropriate convolutions of the winding E. It will be understood that the taps or lead conductors 63 may similarly extend through the end flange 30^a of the stator member 30 to the interior thereof and thence through holes to the appropriate conductors of the winding F. 100

What I claim is:

1. A variometer, vario-coupler or the like comprising hollow coil supports of molded insulating material, coils thereon, rotatable shaft structure, and means within said coils and extending transversely of the axis of said shaft structure holding said hollow coil supports to each other and clamping them at their opposite ends to said shaft structure. 105

2. In apparatus of the character described, rotatable coil structure comprising hollow coil supports of molded insulating material having integral end closure walls, 115 coils on said supports, shaft structure, and means clamping said supports to each other and to said shaft structure.

3. Rotor structure for variometers, vario-couplers and the like, comprising rotor coil supports of molded insulating material, a shaft, an end wall on each of said supports closing one end thereof, said supports together forming a substantially closed casting, and means holding said supports to 120 each other and clamping them to said shaft. 125

4. Rotor structure for variometers, vario-couplers and the like, comprising rotor coil supports of molded insulating material, a shaft, an end wall on each of said supports 130

- closing one end thereof, said supports together forming a substantially closed casing, and means extending from the exterior of one of said supports into said casing and 5 co-acting with the other support to hold said supports to each other and to clamp them to said shaft.
5. Rotor structure for variometers, vario-couplers and the like, comprising rotor coil supports of molded insulating material, a shaft, an end wall on each of said supports closing one end thereof, said supports together forming a substantially closed casing, and means operable from the exterior 10 of said shaft extending into said casing transversely of said shaft for clamping said supports to said shaft.
6. Rotor structure for variometers, vario-couplers and the like, comprising hollow 15 rotor coil supports of molded insulating material, a shaft, and a bolt extending transversely of said shaft and clamping said supports at their opposite ends to said shaft.
7. Rotor structure for variometers, vario-couplers and the like, comprising rotor coil supports of molded insulating material, coils thereon, an inwardly extending end flange on each of said supports, a shaft, and means co-acting with said end flanges and 20 extending through said supports within said coils for clamping said supports to said shaft.
8. Rotor structure for variometers, vario-couplers and the like, comprising hollow 25 rotor coil supports of molded insulating material having inwardly extending end flanges, a shaft, and a bolt co-acting with said flanges disposed adjacent said shaft and extending transversely thereof for clamping 30 said supports to said shaft.
9. Rotor structure for variometers, vario-couplers and the like, comprising rotor coil supports, a shaft, means clamping said supports to said shaft, a bearing member for 35 said shaft, and a collar on said shaft external to the rotor and engaging said bearing member.
10. Rotor structure for variometers, vario-couplers and the like, comprising rotor coil supports, a shaft, means clamping said supports to said shaft, a bearing member for 40 said shaft, and a collar on said shaft external to the rotor and having a conical end engaging in a countersink in said bearing 45 member.
11. Rotor structure for variometers, vario-couplers and the like, comprising hollow 50 rotor coil supports, a shaft, said supports having grooves at their opposite ends in their adjacent edges, and means drawing 55 said supports to each other to cause the walls of said grooves to clamp said shaft at said opposite ends of said supports.
12. Rotor structure for variometers, vario-couplers and the like, comprising hol- 60
- low rotor coil supports, coils thereon, shaft structure, means engaging said supports and extending therethrough and within said coils to clamp them to said shaft structure, said supports having at their adjacent edges 70 co-acting lugs and depressions for pre-determining the positions of said supports with respect to each other.
13. Rotor structure for variometers, vario-couplers and the like, comprising rotor coil supports, a shaft, a shaft supporting member, a collar on said shaft external to the rotor, and resilient means exerting a force longitudinally of said shaft and thrusting said collar against said shaft supporting member. 75
14. In apparatus of the character described, rotatable coil structure comprising coil supports of molded insulating material, coils thereon, shaft structure, and means 80 holding said supports to each other and clamping them to said shaft structure, said shaft structure comprising shaft sections terminating within said supports, an insulating member coupling said shaft sections, and connections from said coils to said shaft sections. 85
15. In apparatus of the character described, rotatable coil structure comprising hollow coil supports of molded insulating material having integral end walls, coils on 90 said supports, shaft structure, and means clamping said supports to each other and to said shaft structure, said shaft structure comprising shaft sections terminating within said supports, an insulating member coupling said shaft sections, and connections from said coils to said shaft sections. 95
16. In apparatus of the character described, the combination with rotatable coil structure comprising a rotatable support, of a coil thereon, shaft structure, a connection from said coil to said shaft structure, a conducting shaft support through which said shaft structure freely extends and having a 100 conical seat, a conical member on said shaft structure engaging in said seat and electrically connecting said shaft structure to said support, and means for thrusting said shaft structure toward said seat. 105
17. A variometer, vario-coupler or the like, comprising stator coil supports, a bearing member between said supports and to which said supports are secured, a rotor comprising rotor coil supports, a shaft, means clamping said rotor coil supports to 110 said shaft, and a collar on said shaft external to the rotor engaging said bearing member. 115
18. A variometer, vario-coupler or the like, comprising a pair of pedestals, a post upstanding from each of said pedestals, stator winding supports secured at their opposite ends to said posts on opposite sides thereof, rotor structure, and means providing 120
- 125
- 130

ing bearings for said rotor structure on said posts.

19. A variometer, vario-coupler or the like, comprising a rotor, shaft structure carrying said rotor, a shaft support providing a bearing for said shaft structure, a second shaft support, and means carried by one of said shaft supports engaging said shaft structure and thrusting it against the other shaft support.

20. In apparatus of the character described, the combination with rotatable coil structure, of shaft structure therefor, a shaft support providing a bearing for said shaft structure, a second bearing member, means carried by said support engaging said shaft structure and thrusting it against said second bearing member, and a winding on said rotatable coil structure, said shaft structure comprising mechanically coupled shaft sections insulated from each other and connected to said winding, said shaft sections connecting said winding with said support and second bearing member.

21. A variometer, vario-coupler or the like, comprising the combination with rotatable coil structure, of shaft structure therefor, a shaft support providing a bearing for said shaft structure, a second bearing member, said shaft structure having a tapered surface, and means engaging said tapered surface forcing said shaft structure against the bearing in said support and thrusting the shaft structure longitudinally against said second bearing member.

22. A variometer, vario-coupler or the like, comprising the combination with rotatable coil structure, of shaft structure therefor, a shaft support providing a bearing for said shaft structure, a second bearing member, said shaft structure having a tapered end, and a spring having an aperture receiving said tapered end, said spring and said aperture engaging said tapered end to force said shaft structure against said bearing in said support and thrusting said shaft structure longitudinally against said second bearing member.

23. A variometer, vario-coupler or the like, comprising the combination with rotatable coil structure comprising a rotatable coil support and a winding thereon, of shaft structure comprising shaft sections insulated from each other and connected to said winding, conducting supports for said shaft structure, one of said supports having a thrust bearing for one of said shaft sections, the other of said supports having a lateral bearing for the other shaft section, and means engaging said other shaft section and thrusting said shaft structure longitudinally.

24. A variometer, vario-coupler or the like, comprising the combination with rotatable coil structure comprising a rotatable

coil support and a winding thereon, of shaft structure comprising shaft sections insulated from each other and connected to said winding, conducting supports for said shaft structure, one of said supports having a thrust bearing for one of said shaft sections, the other of said supports having a lateral bearing for the other shaft section, and means engaging said other shaft section and thrusting said shaft structure longitudinally and laterally against said bearing in said other support.

25. A variometer, vario-coupler or the like, comprising the combination with rotatable coil structure comprising a rotatable coil support and a winding thereon, of shaft structure carrying said rotatable coil support, shaft supports for said shaft structure, a collar on said shaft, and a spring on one of said shaft supports engaging said shaft structure and thrusting it longitudinally to thrust said collar against the other of said shaft supports.

26. A variometer, vario-coupler or the like, comprising rotor and stator structures, said stator structure comprising winding supports having inwardly extending end flanges, a winding on each of said stator supports, and connections to said windings extending through said supports to the interiors thereof and thence outwardly through said flanges.

27. A variometer, vario-coupler or the like, comprising a rotor, posts supporting said rotor, means for securing said posts to a support, stator members secured to opposite sides of said posts, a panel secured to one of said posts and carried thereby free of said support, means attached to said rotor and disposed on the outside of said panel for actuating said rotor, and rotor position-indicating members carried by said means and said panel.

28. A variometer, vario-coupler or the like, comprising a rotor, posts supporting said rotor, stator members secured to opposite sides of said posts, a panel secured to one of said posts, means attached to said rotor and disposed on the outside of said panel for actuating said rotor, and means independent of said panel carried by said posts for mounting said panel and said rotor and stator structure.

29. A variometer, vario-coupler or the like, comprising a rotor, posts supporting said rotor, stator members secured to opposite sides of said posts, a panel of molded insulating material, boss structure integral with said panel and engaging one of said posts, means securing said panel to said one of said posts, and means attached to said rotor and disposed on the outside of said panel for actuating said rotor.

30. A variometer, vario-coupler of the like, comprising a rotor, posts supporting

5 said rotor, stator members secured to opposite sides of said posts, a panel of molded insulating material, boss structure integral with said panel and engaging one of said posts, means extending through said boss structure securing said panel to said one of said posts, and means attached to said rotor and disposed on the outside of said panel for actuating said rotor.

10 31. A vario-coupler or the like, comprising a rotor, posts supporting said rotor, stator members secured to said posts and carrying the stator winding, taps connecting at intervals with said winding, a panel secured 15 to and supported solely by one of said posts, switching mechanism carried by said panel and comprising a plurality of contacts connected with said taps, and a movable switch member carried by said panel and co-acting 20 with said contacts.

32. A vario-coupler or the like, comprising a rotor, posts supporting said rotor, stator members secured to said posts and carrying the stator winding, taps connecting 25 at intervals with said winding, a panel secured to one of said posts, switching mechanism carried by said panel and comprising a plurality of contacts connected with said taps, a movable switch member carried by 30 said panel and co-acting with said contacts, and means independent of said panel carried by said posts for supporting said panel and the rotor and stator.

33. A vario-coupler or the like comprising a rotor, posts supporting said rotor, stator members secured to said posts and carrying the stator winding, taps connecting at intervals with said winding, a panel secured 40 to one of said posts, and a plurality of switching mechanisms carried by said panel and each comprising a movable switch member and a plurality of contacts connected with said taps, said switches located on opposite sides of the axis of rotation of said 45 rotor.

34. A vario-coupler or the like, comprising a rotor, posts supporting said rotor, stator members secured to said posts and carrying the stator winding, taps connecting at intervals with said winding, a panel secured to one of said posts, a plurality of switching mechanisms carried by said panel and each comprising a movable switch member and a plurality of contacts connected with said 55 taps, and rotor position-indicating means comprising a member attached to said rotor and means carried by said panel, said switches being disposed on opposite sides of and below said member attached to said 60 rotor.

35. A vario-coupler or the like, comprising a rotor, posts supporting said rotor, stator members secured to said posts and carrying the stator winding, taps connecting 65 at intervals with said winding, a panel se-

cured to one of said posts, switching mechanism carried by said panel and comprising a plurality of contacts connected with said taps, a movable switch member carried by and rotatable with respect to said panel and co-acting with said contacts, a binding post carried by said panel, and a member connecting said binding post with said switch member and biasing it against said contacts. 70

36. A vario-coupler or the like, comprising a rotor, posts supporting said rotor, the terminals of the rotor winding connecting, respectively, with said posts, rotor circuit binding posts carried by said posts, a stator carried by said posts, taps connecting at 80 intervals with the stator winding, a panel secured to one of said posts, switching mechanism carried by said panel and comprising a plurality of contacts connected with said taps and co-acting movable contact mechanism, and stator circuit binding posts carried by said panel and at least one of them connected with said movable contact mechanism. 85

37. A vario-coupler or the like, comprising a rotor, posts supporting said rotor, stator members secured to said posts and carrying the stator winding, taps connecting at intervals with said winding, a panel secured to one of said posts, switching mechanism carried by said panel and comprising a plurality of contacts connected with said taps, a movable switch member carried by said panel and co-acting with said contacts, and means integral with said panel for limiting the movement of said switch member. 90

38. A vario-coupler or the like, comprising a rotor, posts supporting said rotor, stator members secured to said posts and carrying the stator winding, taps connecting at intervals with said winding, a panel of molded insulating material, boss structure integral with said panel engaging one of said posts, means securing said panel to said one of said posts, switching mechanism carried by said panel and comprising a plurality of contacts connected with said taps, a movable switch member carried by said panel and co-acting with said contacts, and means integral with said panel for limiting the movement of said switch member. 105

39. A variometer, vario-coupler or the like comprising a rotor, posts supporting said rotor, stator members secured to said posts, a panel secured to one of said posts, and means independent of said panel for securing said posts to a support for mounting said panel, rotor and stator members as a unit. 110

40. A variometer, vario-coupler or the like comprising a rotor, posts supporting said rotor, stator members secured to said posts, a panel of molded insulating material, boss structure integral with said panel and engaging one of said posts, means securing 125

said panel to said one of said posts, and means independent of said panel for securing said posts to a support for mounting said panel, rotor and stator members as a unit.

41. A variometer, vario-coupler or the like comprising hollow rotor coil supports of molded insulating material, coils thereon, shaft structure comprising co-axial shaft sections, and means within said coils and extending transversely of the axis of said shaft structure clamping said hollow supports at their opposite ends to the different shaft sections.

42. A variometer, vario-coupler or the like comprising hollow coil supports of molded insulating material, coils thereon, shaft structure comprising co-axial shaft sections, inwardly extending flanges integral with said supports, and means within said coils engaging said flanges and extending through the chamber formed by said supports transversely to the axis of said shaft structure for clamping said supports at their opposite ends to the different shaft sections.

43. A variometer, vario-coupler or the like comprising a pair of conducting members, stator shells of molded insulating material secured at their opposite ends to said members on opposite sides thereof, rotor coil supports of molded insulating material disposed within said shells, co-axial metallic shaft sections bearing, respectively, in said conducting members and electrically connecting therewith, means clamping said rotor coil supports to said shaft sections, and a rotor winding having terminals electrically connected, respectively, with said conducting members through said shaft sections.

44. In a device of the character described, a shell provided with internal windings, a rotor mounted within said shell and provided with external windings, said shell comprising two parts each having lugs on a plurality of sides thereof, the respective lugs on the two parts of said shell being opposed one to the other, and blocks arranged between said lugs and having portions extending beyond said lugs for supporting said device.

45. In apparatus of the character described, a stator member, a rotor mounted within said stator member, and carrying a rotor winding, said stator member comprising two parts carrying windings and each having lugs on a plurality of sides thereof, the respective lugs on the two parts of said stator member being opposed to each other, and blocks disposed between said lugs and having portions extending beyond said lugs for supporting said apparatus.

46. In a device of the character described, a shell formed in two parts, each provided with an internal winding, the two parts of said shell having on a plurality of sides thereof opposed lugs, blocks mounted between said lugs and provided with enlarged end portions to form supports for said shell, and a rotor mounted within said shell and provided with external windings.

47. In apparatus of the character described, rotatable coil structure comprising hollow coil supports of molded insulating material having integral end walls, coils on said supports, shaft structure, and means clamping said supports to each other and to said shaft structure.

ARTHUR ATWATER KENT.
